*Primary Examiner—Louis S. Zarfas**Attorney, Agent, or Firm—Don C. Lawrence***[57] CLAIM**

The ornamental design for a shoe sole, as shown and described.

DESCRIPTION

FIG. 1 is a lateral side elevational view of a shoe sole showing my new design;

FIG. 2 is a bottom plan view thereof;

FIG. 3 is a medial side elevational view thereof;

FIG. 4 is a top plan view thereof;

FIG. 5 is a front elevational view thereof; and,

FIG. 6 is a rear elevational view thereof.

The broken line showing of a shoe upper is for environmental purposes only and forms no part of the claimed design.
